[57] CLAIM

The ornamental design for a container for ice cream, as shown and described.

DESCRIPTION

FIG. 1 is a perspective view of a container for ice cream in accordance with the present invention;

FIG. 2 is a left side view of the container for ice cream as seen in FIG. 1, the right side being a mirror image thereof;

FIG. 3 is a rear view of the container for ice cream as seen in FIG. 1;

FIG. 4 is a front side view of the container for ice cream as seen in FIG. 1;

FIG. 5 is a top view of the container for ice cream as seen in FIG. 1;

FIG. 6 is a bottom view of the container for ice cream as seen in FIG. 1;

FIG. 7 is a left side view of the container for ice as seen in a second embodiment of FIG. 1, the right side being a mirror image thereof;

FIG. 8 is a rear view of the container for ice cream as seen in FIG. 7;

FIG. 9 is a front view of the front side of the container for ice cream as seen in FIG. 7;

FIG. 10 is a view of the top side of the container for ice cream as seen in FIG. 7; and,

FIG. 11 is a rear view of the container for ice cream as seen in FIG. 1.
